UNITED STATES PATENT OFFICE.

FRANK BENJAMIN ROBERTS, OF EUGENE, OREGON.

BOAT.

Application filed April 9, 1925. Serial No. 21,920.

This invention relates to a boat construction and aims to provide a novel form of propelling means, whereby the larger portion of the weight of the boat is sustained by the propelling means.

Another object of the invention is to provide a paddle wheel which will be supported in such relation with the surface of the water as to cause only a small surface of the wheel 10 and the blades forming a part thereof to contact with the water, thereby reducing the resistance to the movement of the paddle wheel, to the minimum.

With the foregoing and other objects in view which will appear as the description proceeds, the invention resides in the combination and arrangement of parts and in the details of construction hereinafter described and claimed, it being understood that 20 changes in the precise embodiment of the invention herein disclosed, may be made within the scope of what is claimed, without departing from the spirit of the invention.

Referring to the drawings:

Figure 1 is a plan view of a boat constructed in accordance with the invention.

Figure 2 is a sectional view through the boat.

Figure 3 is a sectional view through one 30 of the paddle wheels.

Figure 4 is a sectional view through one of the forward paddle wheels.

Figure 5 is a sectional view taken on line 5—5 of Figure 3.

Figure 6 is a sectional view through one 35 of the pontoons.

Referring to the drawings in detail, the body portion of the boat is in the form of a pontoon 5 which is formed with a central 40 cut out portion to accommodate the paddle wheels. Bearing members 6 are provided at the rear of the cut out portions and accommodate the shaft 7, on which the paddle wheels 8 are secured.

Each paddle wheel is hollow as clearly 45 shown by Figure 5 of the drawings and embodies the central tubular member 9 and an outer member 10, the outer member being secured to the tubular member by means of 50 the end walls 11. The outer member 10 is formed with offset portions 12, the offset portions 12 presenting walls 13 curved transversely of their lengths providing blades that contact with the water to force the boat 55 over the water.

In each tubular member 9 of the rear paddle wheels are the bars 14 that connect the paddle wheels to the shaft 7, the shaft 7 being supplied with a suitable ring gear 15 that meshes with the pinion 16 of the drive 60 shaft 17 that receives rotary motion from the engine 18, as through the shaft 19 and gearing 20.

The forward paddle wheels also include 65 tubular members 21 in which the securing members 22 are positioned, which securing members have connection with the stub shafts 23 that are pivotally supported at the outer ends of the shaft 24, the connection between the shaft 24 and stub shafts 23 being such 70 as to permit the forward propeller wheels to pivot in horizontal planes to accomplish the steering of the boat.

Rods 25 have connection with the stub 75 shafts 23 which in turn are connected with the steering rod 26 that carries the usual steering wheel 27 on the outer end thereof, the steering wheel being disposed in proximity to the operator's seat to permit the boat to be controlled with efficiency.

Disposed intermediate the ends of the 80 paddle wheels are blades 28 which blades prevent lateral movement of the paddle wheels or sliding thereof to hold the boat to its course.

From the foregoing it will be seen that 85 due to the construction as shown and described, the paddle wheels which are hollow, assist in supporting the weight of the boat proper and at the same time allow only the 90 propelling portions thereof to move through the water thereby reducing the resistance to a minimum.

Having thus described the invention what 95 is claimed as new is:—

1. In a boat construction, a body portion 100 comprising a pontoon having a central cut out portion, transversely extending shafts disposed adjacent to the ends of the cut out portion, paddle wheels on the shafts, each paddle wheel comprising a central tubular member, an outer member having offset portions defining shoulders, means at the ends of the tubular members for connecting the tubular members and outer members providing air compartments, and means for transmitting movement to the shafts and paddle wheels.

2. In a boat construction, a body portion 105 having a central cut out portion, shafts ex- 110

tending transversely of the body portion and disposed adjacent to the ends of the body portion, paddle wheels supported on the shafts and operating within the cut out portion of the body portion, means for imparting rotary movement to the shafts and paddle wheels, and means for supporting the

paddle wheels at one end of the cut out portion to permit movement thereof in horizontal planes.

In testimony that I claim the foregoing as my own, I have hereto affixed my signature.

FRANK BENJAMIN ROBERTS.
